United States Patent Office.

NICHOLAS S. VEDDER, OF TROY, NEW YORK.

Design No. 2,735, dated August 6, 1867.

DESIGN FOR THE PLATES OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Design for Stove-Plates, of which the following is a full and exact description; reference being had to the accompanying photographs, in which—

Figure 1 represents a side plate, and

Figure 2 a door on a larger scale of a stove having my said design.

The design for the side plate consists of the horizontal and vertical rope-like mouldings *k* with rosettes *l* at their crossings, and intervening vertically-ribbed panels *m*, all shaped and arranged within a border moulding *n*, so as to appear as represented in fig. 1; and the door is ornamented by a series of alternate vertical rope-like mouldings *o* and plane strips *p*, with cross-straps *q q*, all shaped and arranged as represented in fig. 2.

What I claim as my invention or production, and desire to secure by Letters Patent, is—

The design for stove-plates herein set forth and shown.

NICHOLAS S. VEDDER.
